WINDOW SASH CONSTRUCTION

James R. Walker, Lansing, Mich.

Application March 26, 1949, Serial No. 83,573

1 Claim. (Cl. 20—52.4)

1

This invention relates to window sashes, is particularly concerned with window sash construction, is more particularly concerned with a device whereby the sashes may readily be raised and lowered and whereby the sashes may be adjusted at substantially any desired position, and is still more particularly concerned with weather stripping to prevent cold air from entering into the building, and is most particularly concerned with runways disposed between the side rails of the sash and the side members of the frame and adapted for the smooth movement of the said sashes.

There are presently many window sash constructions to be had, and there are many devices adapted for raising and lowering of window sashes. However, the devices presently had for raising and lowering, and adjusting sashes in position, rely principally on devices having sash weights. Sash weights are not only unwieldy of installation but are extremely awkward of repair. Such devices are for other reasons quite undesirable.

It is therefore an object of the present invention to provide a sash construction. It is a further object to provide a window sash construction whereby the sash may readily be raised and lowered. It is a further object to provide a window sash construction whereby the sash may readily be adjusted in any desired position. It is still a further object to provide a window sash weather stripping. A further object of this invention is the provision of a window sash construction having ease of construction and having economy of fabrication.

I have now discovered and invented in a window sash construction, a frame, an upper sash, a lower sash, two pairs of sash runways, each of the said sashes having a runway disposed on either side thereof, each of the said runways being interposed between the side rails of each of the sashes and the said frame, the runways of each side of the said frames being disposed back to back in respect to each other, a recess in each side rail of each of the sashes being adapted for conforming of the said runways with the side rails of the said sashes, four coil springs, each of the said runways an open space, each of the said spaces having longitudinally disposed therein the said space one of the said springs, each of the said springs being secured at their upper ends of the said frame, the lower ends of each of the said springs being secured to the lower bottom rails of each of the two sashes, and the said springs being arranged to hold the said

2

sashes in their adjusted position, and I am now able to avoid the disadvantages of the prior art and am able to accomplish the objects set forth.

Referring to the drawings:

Fig. 1 is an elevation view of a window and frame from the room side.

Fig. 2 is a vertical section taken along the lines 2—2 of Fig. 1.

Fig. 3 is a cross section view of the runways device into which the sash conforms.

Fig. 4 is a horizontal section taken along the lines 4—4 of the Fig. 1.

Fig. 5 is a vertical section taken along the lines 5—5 of the Fig. 1.

In the Fig. 1 the lower window pane 1 is set into the side rails 2, the bottom rail 3, and the inside meeting rail 4. The upper window pane 1 is set into the side rails 2a, the top rail of the upper frame, and the lower inside meeting rail 5 of the upper frame. The numeral 13 designates the vertical stops from the interior of the room, and the numeral 14 designates the vertical stops from the weather side. The numeral 8 designates the runway device for the lower sash.

The Fig. 2 is a vertical section taken along the line 2—2 of Fig. 1, and shows the longitudinal right side view of the runway device 8a for the upper sash. The numeral 9 designates the coil spring for the lower sash. The numeral 10 designates the coil spring for the upper sash. The clip 10a is formed from the spring 9, and the said clip 10a is held over the upper end of the runway 8. The clip 10b is formed from the spring 10, and the said clip 10b is held over the upper end of the runway 8a.

In the Fig. 5 is shown the weather stripping 6 set into the rail 5, at the meeting of the said rail 5 and the rail 4. One edge of the said weather stripping 6 is set into a longitudinal groove formed in the frame 5, and the said stripping is frictionally held thereto by the said frame.

In the Fig. 4 a cross section of the two runways are shown in small scale, while in the Fig. 3 is shown a cross section of the runway in larger scale. In the Fig. 4 the recess 7, cut into the side rails 2 and the side rails 2a is shown.

The lower end of the spring 9 is secured to the thin steel bar 11. The lower end of the spring 10 is secured to the thin steel bar 12. The steel bars 11 and 12 are nailed to the lower ends of the side rail 2, and 2a respectively.

Referring now to the Fig. 3 in which the larger cross sectional view of the runway is shown, the numeral 15 designates the outer side wall of the runway, the numeral 16 designates the inner

side wall of the runway, and 17 the arch of the runway, which arch rests against the middle of the side rails. The side rails of the sash are movable between the members 15 and 16. The numerals 18, 19, and 20 designate the flat surfaces, and are merely a continuation of the member 16. The numeral 21 designates an angle continuation from the surface 20, and the edge bent upon itself. The numeral 22 designates the space in the runway for holding the spring 9, and the spring 10. The numeral 23 designates the opening between the member 16 and the angle 21 through which the bar 11, or bar 12, projects to engage the lower end of the spring 9 or the spring 10. The numeral 24 designates the edges of the arch 17.

The window frame comprises the window sill 25, the under surface 26, and the two side frames. The lower sash is bordered at the bottom by the sill 25, and is bordered at each of its sides by each of a pair of runways 8 and 8a, disposed as shown in Fig. 4. The springs 9 of the lower sash are disposed within the space 22 of the runway, and are secured at the top end by the clips 10a, which clips are part of the springs, to the upper end of the runways. The lower end of the said springs 9 of the lower sash is secured to the bar 11.

I wish to point out that the structure of the runway is specifically fabricated and when seen from the cross section view as in the Fig. 3, the outer side wall is folded somewhat upon itself, the arch 17 is substantially 80 degrees in respect to the said outer wall, the flat surface 18 is substantially 90 degrees from the flat surface 19, the flat surface 19 is substantially 90 degrees in respect to the flat surface 20, and the angle continuation from the surface 20, which is the second outer wall is substantially 90 degrees from the surface 20.

I wish particularly to point out that in the window sash construction of my invention there is great ease and economy of fabrication. The runways may be constructed of light gauge sheet metal and the machinery therefore is very inexpensive of construction. The assembly of the runways with the rest of the window construction can be accomplished without the need of any special machinery, and without the need of any special skill; an ordinary carpenter can make the complete assembly with ease.

No sash weights are required and the assembly of the sash construction is accomplished after the frames of the windows are completed, and there is no need for tearing down the frames for the construction. In the event of repair, there is no need to remove the window frames, since the springs which replace the sash weights can easily be repaired or replaced by simply remov-

ing the vertical stops, removing the sashes, and making any necessary repair or replacement. I want further to point out that great versatility of the construction is possible. The entire construction comprising the frames, sashes, and all other members may be fabricated, assembled, or not assembled, in the plant, as it is most convenient to the builder or the fabricator.

The window construction of my invention may be used on any knocked-down window frame; and the frames can be made at the point of the cheapest manufacture. The rabbeting on the side rails may be done at the point of sale after the sashes have been assembled. There is no need for varying transverse sizes of runways since the runway of a given transverse size is adaptable for any window construction, and all that is necessary is to vary the length of the runways. To adjust for the varying weights of window sashes, it is only necessary that the diameter of the spring wire vary from substantially 0.141 inches for the smallest and lightest sash, to 0.064 inches for the largest and heaviest sash. The length of the spring varies according to the height of the component sashes.

I claim:

In a window sash construction, a sheet metal runway comprising a narrow outer wall, the said outer wall being substantially folded upon itself, an arched surface, the said arched surface extending therefrom the said outer wall and the said arched surface being substantially eighty degrees in respect to the said outer wall, an inner wall, the said inner wall extending from the arched surface and formed by folding of the sheet metal upon itself, a flat surface, the said flat surface extending from the said inner wall, a second flat surface, the second flat surface extending from the first flat surface in a direction substantially ninety degrees from the first flat surface, a third flat surface, the third flat surface extending in a direction substantially ninety degrees from the second flat surface, a second outer wall, the said second outer wall being folded upon itself and extending from the third flat surface in a direction substantially ninety degrees from the said third flat surface.

JAMES R. WALKER.
